UNITED STATES PATENT OFFICE.

LISBETH LINDEMANN, OF MUNICH, GERMANY.

NON-TRANSPARENT ORNAMENTED TILE FOR DECORATIVE PURPOSES.

SPECIFICATION forming part of Letters Patent No. 634,851, dated October 10, 1899.

Application filed November 8, 1898. Serial No. 695,872. (No specimens.)

To all whom it may concern:

Be it known that I, LISBETH LINDEMANN, a subject of the King of Bavaria, residing at Munich, Kingdom of Bavaria, Germany, have 5 invented new and useful Improved Ornamented Tiles for Decorative Purposes, of which the following is a full, clear, and exact description.

The present invention relates to non-transparent ornamental glass tiles or plates for decorative purposes on which the light is intended to fall.

The object of the invention is to attain greater brilliancy and liveliness of the effective color as also greater durability of the tiles or plates.

In order to render the present specification more readily understood, reference is had to the accompanying drawings, in which similar letters of reference denote similar parts throughout both views.

Figure 1 is a vertical cross-section, and Fig. 2 a front elevation, of the tile or decorative glass plate.

The tile or plate consists of two pieces of glass, the front plate *a* having the painting at the back thereof, while the background is formed by a second plate *b*, arranged at a suitable distance from the front plate. According to the invention the front plate *a* consists of plate-glass having an uneven outer surface, said surface being provided with more or less flat or shallow corrugations, while the inner surface of the said plate is somewhat 35 rough and scratched or provided with slight cracks. Both surfaces are so arranged to effect certain light and shade results, the inner surface serving at the same time to more readily receive and retain the color. The latter object is best attained by means of the so-called "cathedral" glass. The painting is advantageously so carried out that the background *f* of this plate is left uncolored—*i. e.*, remains transparent—the background proper 40 of the complete tile or plate being formed by the rear plate *b*. The back of the rear plate

b is covered with a coating of a bright non-transparent color, as indicated at *c*, so that the same will reflect. This effect may be attained by coating the same with a bright 50 paint, the tone of which should be chosen so as to suit the reflection and shading of the painting in the light of the room to be decorated. The rear plate is advantageously of plate-glass, (transparent,) or the above-mentioned cathedral glass may be employed. The two plates are spaced apart and fixed together in any well-known manner. The space between them is formed by fixing a frame of cork or the like around the edges between 60 the plates, the edges being inclosed in hollow frame-pieces filled out with putty or the like to prevent dust and damp from penetrating between the plates.

The peculiar effect attained by the present decorative plates is due to the manifold breaking 65 of the rays and to reflection of the rays on and between the two plates, the unevenness of the plates bringing these effects into particular prominence. The shade effect of 70 the painting and the unevenness of the front plate in combination with their effect on the rear plate render the representation particularly pleasing.

I claim as my invention—

An ornamented tile for decorative purposes, the same comprising a supporting-frame, a front plate of glass having an uneven outer surface, and provided on its inner surface with a painted ornament or design, the said 80 inner surface being roughened or scratched, and a rear plate separated from the front plate by a space, the back or outer surface of said rear plate being coated with a bright non-transparent coloring, as described. 85

In witness whereof I have hereunto set my hand in presence of two witnesses.

LISBETH LINDEMANN.
